UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

MOTORMAN'S VALVE.

No. 845,385.

Specification of Letters Patent.

Patented Feb. 26, 1907.

Application filed March 17, 1906. Serial No. 308,506.

To all whom it may concern:

Be it known that I, FRED B. COREY, a citizen of the United States, residing at Schenectady, in the county of Schenectady and State 5 of New York, have invented certain new and useful Improvements in Motormen's Valves, of which the following is a specification.

My invention relates to a motorman's or engineer's valve; and its object is to provide 10 a valve having a number of novel and advantageous features.

One feature of my invention relates particularly to valves of the rectilinear reciprocating type. It has ordinarily been the practice in such valves heretofore to groove the 15 valve-seat to form both the slide and the lateral guides for the valve. Such a valve-seat, however, is difficult to grind properly, and consequently some valves have been arranged heretofore with raised seats. In such 20 a valve the seat itself cannot act as a guide, and when the walls of the bonnet or casing are used to form the lateral guides for the valve it restricts the opening into the bonnet, 25 and ordinarily necessitates some special arrangement of the operating-handle on account of the difficulty of machining the inside of the bonnet in the usual way.

One feature of my invention consists in 30 forming the valve-seat with a raised slide, but providing a loose yoke resting on the valve-seat on opposite sides of the slide adapted to form the lateral guides for the 35 valve and to be pressed by the bonnet upon the seat. With this arrangement the advantages of the raised seat are obtained, while at the same time the disadvantages of a restricted opening at the bottom of the bonnet are avoided, so that a standard arrangement 40 of the operating-handle is possible.

Another feature of my invention relates to the guard for the end of the operating-spindle that projects beyond the casing. It has been proposed heretofore to surround the 45 outer end of the spindle by a guard or shroud so arranged as to make it impossible to move the spindle except by means of a handle adapted to enter the shroud, and thus to prevent the valve being moved by meddlesome persons. One form of shroud that has been used heretofore comprises an incomplete ring supported by a casing and lying substantially flush with the end of the spindle. The opening in the ring was left for the

passage of a projection on the handle when 55 the handle is applied and removed, so as to insure that the valve is left in lap position when the handle is removed. In order that the valve might be moved after this projection on the handle had passed through the 60 open portion of the ring when applying the handle, the lower portion of the shroud was cut away on each side of the open portion, so that circumferentially - projecting tongues were formed, which were likely to be broken 65 off.

One feature of my invention consists in forming the shroud of a complete ring, so as to give it maximum mechanical strength, and in order to provide for insuring the removal of the handle only when the valve is in lap position I provide the ring with a projecting flange having a slot through which a projection on the handle must pass when the handle is removed. 75

My invention will best be understood by reference to the accompanying drawings, in which—

Figure 1 shows an elevation in cross-section of a motorman's valve constructed in accordance with my invention. Fig. 2 shows an elevation in cross-section on the line 2 2 of Fig. 1 of the valve-seat, valve, and yoke. Fig. 3 shows a perspective view of the valve with the bonnet removed, and Fig. 4 shows a 85 plan view of the shroud.

In the drawings, A represents the valve-seat, which is provided with a raised slide a, provided with the usual ports. Since this slide projects above the breast of the surface 90 of the valve-seat, it may readily be ground perfectly true.

B represents a valve adapted to be reciprocated on the slide a.

C represents a loose yoke which rests on the 95 valve-seat on each side of the slide a and which is adapted to serve as lateral guide for the reciprocating valve B.

The yoke C is pressed down upon the valve-seat A by the compression-spring D, 100 the lower end of which has a bearing in the socket e, formed for this purpose on the yoke C.

The valve B is transversely slotted, as is shown in Figs. 2 and 3, to receive the block 105 E, (shown in Fig. 1,) which is engaged by a stud f, carried eccentrically by a flange f' on the operating-spindle F, which extends

through the casing G. By rotating the spindle F the valve B is moved rectilinearly on its seat.

The upper side of flange f' bears against the surface f'' on the inside of the casing or bonnet G, and it is evident that this surface should be ground so as to be practically airtight. It is evident that if the yoke C were formed integral with the bonnet G grinding this surface would be a very difficult matter. Since, however, the yoke C is a loose member, the opening at the bottom of the bonnet is as wide as in a valve of the rotary type, and free access is obtained to the surface f'' for grinding.

It will be seen that the socket c is in line with the axis of the spindle F and that the upper end of the compression-spring D does not bear directly on the bonnet, but instead has a bearing in a socket in the spindle F. Consequently this single spring serves both to press the yoke C upon the valve-seat, as has been mentioned above, and also to press the flange f' upward against the surface f'' of the bonnet G.

In order to prevent meddlesome tampering with the valve, the bonnet G carries a shroud g, which surrounds the outer end of the spindle F and lies practically flush with the end of the spindle. This shroud g is in the form of a complete ring, as shown in Fig. 4, and consequently may be designed with any desired mechanical strength, and is provided with an outwardly-projecting flange 35 g', which has a deep slot g'' and two notches at g'' . The shroud is preferably cut away at the bottom, as indicated at g'' in Fig. 1, so that dust and dirt may readily be removed. H represents the operating-handle, which is provided with a portion h, adapted to enter the shroud g and engage the squared end of the spindle F, so as to operate the valve. The handle also is provided with a projecting tongue h', adapted to pass through the slot g'' in the flange g' when the handle is applied and removed. This tongue h' and the slot g'' insure that the handle will be removed only when the valve is in lap position. The handle is also provided with the usual spring-50 pressed member h'', adapted to engage the notches g'' in the flange g' when the valve is moved to its operative positions.

What I claim as new, and desire to secure by Letters Patent of the United States, is—

1. In combination, a valve-seat having a raised slide provided with ports, a valve adapted to be reciprocated on said slide, a loose member resting on said seat and adapted to form lateral guides for said valve, an inclosing bonnet or casing adapted to engage said member and to press said member upon said seat.

2. In combination, a valve-seat having a raised slide provided with ports, a valve adapted to be reciprocated on said slide, a

loose member resting on said seat and adapted to form lateral guides for said valve, an inclosing bonnet or casing, and a compression-spring interposed between said member and said bonnet adapted to press said member on said seat.

3. In combination, a valve-seat having a raised slide provided with ports, a valve adapted to be reciprocated on said slide, a loose yoke resting on said seat on both sides of said slide and adapted to form lateral guides for said valve, an inclosing bonnet or casing adapted to engage said yoke and to press it on said seat, a rotatable spindle extending through said bonnet perpendicularly to said slide, and connections between said spindle and said valve whereby the rotary movement of the spindle reciprocates the valve on the slide.

4. In combination, a valve-seat having a raised slide provided with ports, a valve adapted to be reciprocated on said slide, a loose yoke resting on said seat on both sides of said slide and adapted to form lateral guides for said valve, an inclosing bonnet or casing, a compression-spring interposed between said yoke and said bonnet adapted to press said yoke on said seat, a rotatable spindle extending through the bonnet perpendicularly, to said slide, and connections between the spindle and the valve whereby the rotary movement of the spindle reciprocates the valve on the slide.

5. In combination, a valve-seat having a raised slide provided with ports, a valve adapted to be reciprocated on said slide, a loose yoke resting on said seat and adapted to form lateral guides for said valve, an inclosing bonnet or casing, an operating-spindle extending through said bonnet perpendicularly to the slide and operatively connected to the valve, a flange on said spindle adapted to bear against the inner side of said bonnet, and a compression-spring interposed between said spindle and said yoke adapted to press said flange against the bonnet and the yoke against the seat.

6. In combination, a valve-seat having a raised slide provided with ports, a valve adapted to be reciprocated on said slide, a loose yoke resting on said seat and adapted to form lateral guides for said valve, an inclosing bonnet or casing, an operating-spindle extending through said bonnet perpendicularly to the slide and operatively connected to the valve, a flange on said spindle adapted to bear against the inner side of said bonnet, a socket carried by said yoke in line with the axis of said spindle, and a compression-spring bearing at one end in said socket and at the other against said spindle.

7. In combination, a valve, an inclosing casing therefor, an operating-spindle for the valve extending through the casing, a shroud surrounding the outer end of the spindle

comprising a complete ring carried by said casing and lying substantially flush with the end of said spindle, and a handle having a portion adapted to enter said shroud and engage said spindle.

8. In combination, a valve, an inclosing casing therefor, an operating-spindle for the valve extending through the casing, a shroud surrounding the outer end of the spindle comprising a complete ring carried by said casing and lying substantially flush with the end of said spindle, an outer slotted flange carried by said shroud, and a handle having a portion adapted to enter said shroud and engage said spindle and a second portion adapted to pass through the slot in said flange.

9. In combination, a valve, an inclosing casing therefor, an operating-spindle for the valve extending through the casing, a shroud

surrounding the outer end of the spindle comprising a complete ring carried by said casing and lying substantially flush with the end of said spindle, an outer flange carried by said shroud having a slot and a plurality of notches, a handle having a portion adapted to enter said guard and engage said spindle and a second portion adapted to pass through the slot in said flange, and means carried by the handle for yieldingly engaging the notches in said flange in the several positions of the valve.

In witness whereof I have hereunto set my hand this 16th day of March, 1906.

FRED B. COREY.
